DESIGN FOR A COMBINATION CELLARETTE AND ASH RECEIVER

Roger L. Walters, Macon, Ill.

Application January 18, 1938, Serial No. 74,396

Term of patent 7 years

To all whom it may concern:

Be it known that I, Roger L. Walters, a citizen of the United States of America, residing at Macon, county of Macon and State of Illinois, have invented a new, original, and ornamental Design for a Combination Cellarette and Ash Receiver, of which the following is a specification, reference being had to the accompanying drawing forming a part thereof, in which:

Fig. 1 is a perspective view of a combination cellarette and ash receiver showing my new design.

Fig. 2 is a perspective view of the same showing the inner compartment in raised position.

I claim:

The ornamental design for a combination cellarette and ash receiver as shown and described.

ROGER L. WALTERS.
